TRIMMING FIXTURE FOR PIEZOELECTRIC RESONATOR MEASURING APPARATUS

Alfred G. Staples, Evergreen, Va., assignor to General
Electric Company, Lynchburg, Va.

Filed Sept. 17, 1974, Ser. No. 506,892

Term of patent 14 years

Int. Cl. D10—04

U.S. Cl. D10—75

FIG.1

FIG.2

FIG. 3

FIG. 1 is a perspective view of a trimming fixture for piezoelectric resonator measuring apparatus taken from the upper left front;

FIG. 2 is a perspective view of the trimming fixture for a piezoelectric device taken from the upper right rear; and

FIG. 3 is a top view of the trimming fixture for a piezoelectric device.

The bottom of the trimming fixture for a piezoelectric device is essentially plain and undecorated.

I claim:

The ornamental design for a trimming fixture for piezoelectric resonator measuring apparatus, as shown and described.
